UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

1,368,333.

Specification of Letters Patent. Patented Feb. 15, 1921.

Application filed May 6, 1918. Serial No. 232,838.

To all whom it may concern:

Be it known that I, GEORGE GODDU, a citizen of the United States, residing at Winchester, in the county of Middlesex and 5 State of Massachusetts, have invented certain Improvements in Fastening-Inserting Machines, of which the following description, in connection with the accompanying drawings, is a specification, like reference 10 characters on the drawings indicating like parts in the several figures.

This invention relates to machines for inserting fastenings in boots and shoes, and more particularly to fastening inserting machines in which provision is made for varying 15 the spacing between fastenings inserted by the inserting mechanism.

In one type of machine used for the purpose of inserting fastenings, the construction 20 comprises a laterally movable head provided with guideways in which the awl and driver bars, respectively, are vertically reciprocable, the arrangement being such that the awl is first depressed to penetrate 25 the stock; the head moved laterally while the awl is still in engagement with the stock to feed the same, the awl then withdrawn and the head moved laterally back to its original position to bring the driver into 30 position over the opening previously made in the stock by the awl, and finally a fastening is supplied and driven by the driver into the stock. The driver is then raised thus completing the cycle of operation. In such 35 a construction, it is occasionally necessary or desirable to adjust the awl with respect to the driver in order to vary the spacing between fastenings. Inasmuch as the horizontal distance between the awl and the 40 driver must be exactly equal to the length of the feeding stroke of the movable head, adjustment of the awl with respect to the driver must be followed by a corresponding adjustment in the connections by which the 45 reciprocatory movement of the head is effected. Heretofore it has been necessary, in all the practical machines with which applicant is familiar, to adjust the awl with respect to the driver and then, by separate 50 and distinct means, effect a corresponding adjustment in the movements of the reciprocatory head. Inasmuch as these adjustments must be made with a fine degree of

accuracy, more skill is required than is usually displayed by the average operative 55 in a shoe factory who is a shoe worker rather than a machinist. In any case, the time required to make the necessary adjustments is prohibitive when it is desired to change the spacing between fastenings frequently as in repair work.

Accordingly it is an object of the present invention to provide improved means for effecting adjustment of the awl with respect to the driver and simultaneously corresponding adjustment in the extent of feeding movement of the awl. By the improved mechanism thus provided, any operative can 60 adjust his machine to vary the spacing between fastenings and that with such a degree of ease and accuracy as to render the machine quickly adaptable to a wide range of work. Preferably the said means is so constructed as to be comprised in a unitary 65 structure arranged for sliding movement 70 with respect to the inserting mechanism.

It is a further object of the invention to provide improved means for adjusting the awl with respect to the driver of such a character as will be especially simple in construction and efficient in operation. In the 75 illustrative construction the said means comprises a member mounted preferably on the awl carrier, for ready adjustment along a path substantially parallel to the direction of penetrative movement of the awl for 80 adjusting the awl relatively to the driver.

Other features of novelty which contribute to the carrying out of objects of the invention hereinbefore enumerated or of 85 other objects of the invention which will be apparent from a consideration of the disclosure of the invention in the specification and drawings will be pointed out in the following detailed description and included in 90 the claims.

In the drawings,

Fig. 1 is a front view of part of a fastening inserting machine showing one embodiment of the invention;

Fig. 2 is a view in perspective of the same machine showing details of the awl adjusting mechanism;

Fig. 3 is a detail view showing parts of the awl adjusting mechanism;

Fig. 4 is a detail, sectional view showing

100

105

the manner of securing the adjustable member of the awl adjusting mechanism in adjusted position;

Fig. 5 is a detail sectional view along the 5 line 5—5 of Fig. 2, and

Fig. 6 is a detail view of the lower portion of the awl bar carrier.

For the purpose of illustration the invention is shown as embodied in a fastening 10 inserting machine of the type disclosed in the patent to Goddu, No. 490,624, granted January 24, 1893, to which reference should be had for a fuller disclosure of the fastening inserting mechanism. In the drawings, 15 the fastening inserting mechanism is shown as carried upon a head 8 which is mounted upon the machine frame 9 for oscillation laterally and in a direction parallel to the plane defined by the driver 10 and the awl 12. A guideway 14 is provided in the head 8 for the driver bar 16, the latter being lifted by the cam 18 and given its operative stroke through the lever 20 under the action 20 of spring 22. Pivoted to the head 8 at the point 24 is an awl bar carrier 26 having formed therein a guideway 28 for the awl bar 30 which carries the awl 12. Provision is made for adjustably mounting the awl on the awl bar by means of a block 32 arranged 25 to be adjustably clamped to the awl bar to secure the awl selectively in any one of a plurality of positions with respect to the lower end of the awl bar, so that the awl may be adjusted toward or from the driver. 30 Mounted upon a shaft 34, which has bearing in the machine frame, is a lever 36 having a rack 38 at its end arranged to mesh with a rack 40 at the upper end of the awl bar to give the latter positive reciprocation 35 toward and from the work carried by the horn 42. Extending laterally from the head 8 is an arm 44 slotted as at 46 to receive slidably a block 48 mounted on a second block 50 in turn mounted to slide 40 in the guideway 52 of an arm 54 fixedly attached to the shaft 56 mounted in the machine frame, said shaft carrying at its opposite end a lever 58 provided with a roll 60 running in a cam slot in cam 62 on the main 45 shaft. It will be obvious that upon rocking the shaft 56 the head 8 will be oscillated and that the extent of this oscillation may be varied by adjusting the connecting blocks 50 and 48 in their respective guideways in 50 the arm 54 and in the arm 44 of the head 8. These blocks 48 and 50 are secured in adjusted position by means of the set screw member 64 which has a screw threaded portion to coöperate with the interiorly screw 55 threaded portion of block 50. Thus member 64 by exerting pressure on the bottom of the slideway 52 causes the block 50 frictionally to engage the walls of the slide-way to be held fixedly in adjusted position. 60 65 As shown in Fig. 4, the length of the mem-

ber 64 from the collar 65 to the end which engages the floor of the guideway is slightly greater than the dimension of block 50 along the plane of section, thus permitting the end of member 64 to engage the slotted 70 face of the arm 54 to cause frictional engagement of block 50 in the slideway before collar 65 contacts with the end of block 50. Mounted upon the outer end of the securing member 64 is another block 66 arranged to slide in a slot 68 in the awl bar carrier 26. Thus when the blocks 48 and 50 are adjusted vertically in their respective guideways the block 66 is moved at the same time and to the same extent along its guide-way in the awl bar carrier 26. 75 80

In the operation of the machine, the awl 12 is first depressed to cause it to penetrate the work, after which while the awl remains in the work the head 8 and awl carrier 26 are swung to the left on the machine frame, as seen in Fig. 1, by the arm 54 and blocks 48, 66 to feed the work. Upon the termination of the movement of the head 8 to the left, the awl is withdrawn from the work, 90 and the head 8 is swung back to its original position in order to bring the driver over the opening made in the work by the awl. The driver is then forced downwardly to insert a fastening into the work, after which 95 it is again raised, thus completing a cycle of operations of the machine. When the driver is in driving position, as shown in Fig. 1, both the guideway 52 in the arm 54 and the slot 46 in the arm 44 of the swinging head 8 are vertically disposed. Consequently, if the blocks 48 and 50 are adjusted upwardly or downwardly in the slot 46 and guideway 52 respectively, the path of movement of the driver in inserting a fastening 100 into the work, or, in other words, the line of drive of the fastenings will not be affected. It is manifest, however, that if the blocks 48 and 50 are adjusted upwardly, the range of movement of the swinging head 8 and awl 105 carrier 26 is decreased, whereas, if the blocks 48 and 50 are adjusted downwardly, the range of movement of the swinging head and the awl carrier is increased. It follows, therefore, assuming that in one position of the parts, the driver and the awl are so spaced that the opening made in the work by the awl will be presented exactly in the line of drive, that if the blocks 48 and 50 were adjusted upwardly in the slot 46 and guideway 52 so as to decrease the extent of swinging movement of the head and the awl carrier without changing the spacing of the awl and the driver, the awl 12, by reason of being then spaced from the 110 driver by a distance greater than the extent of swinging movement of the awl carrier, would not be moved far enough to carry the opening made in the work by it to the line of drive of the fastenings. Con- 115 120 125 130

versely, if the blocks 48 and 50 were adjusted downwardly in the slot 46 and guideway 52 respectively, and the relative spacing of the driver and the awl remained unchanged, the awl would, upon subsequent movement of the swinging head 8 to the left, carry the opening made by it in the work beyond the line of drive, so that in neither case would the opening made by the awl be properly alined with the driver after adjustment of the length of feeding movement of the work. In order to cause the opening made in the work by the awl to be accurately located in the line of drive of the fastenings regardless of variations in the range of feeding movement of the work, the slot 68 in the awl bar carrier 26 is slightly inclined downwardly toward the driver, the degree of inclination being such that when the blocks 48, 66, and 50 are moved downwardly in the slots 46 and 68 and the guideway 52 respectively to increase the range of feeding movement of the work, the awl 12 will be moved away from the driver through a distance equal to the increment in the range of work feeding movement and, conversely, when the blocks 48, 66 and 50 are moved upwardly in the slots 46 and 68 and the guideway 52 so as to decrease the range of feeding movement of the work, the awl 12 will be moved toward the driver through a distance equal to that by which the range of feed of the work is decreased.

In order that the adjustable blocks may be readily shifted in their guideways, a member 70 is attached to the block 50 and is provided with a handle for the ready manipulation of the parts to which it is attached. To adjust the slidable blocks it is necessary only to loosen the securing member 64, by means of a screw driver, move the blocks by hand through the handle 70 and again adjust the securing member 64 to secure the blocks fixedly in position with relation to the arm 54. It will be noted that the means for adjusting the awl with respect to the driver and the means for adjusting the feeding stroke of the awl are bodily movable in a right line toward and from the awl. Conveniently a scale or indicator is provided as a guide for the operator in making the desired adjustments.

In repair work especially, it is frequently desired to change the extent of feeding movement of the work between successive fastening insertions, and it is, therefore, particularly to be desired in a machine designed to be used for repair work that it be capable of being adapted readily and quickly to insert fastenings at various spacings. Heretofore, however, it has been necessary in all of the machines in practical use with which applicant is acquainted, to adjust the awl in the awl bar in a direction toward or from the driver and then by a separate adjustment provide for a corresponding change in the extent of oscillation of the swinging head and therefore in the feeding stroke of the awl. Much time and labor were often consumed in making these adjustments as the greatest degree of accuracy is required. Otherwise the fastening will not be driven into the perforations made by the awl. It will be understood that, in order to drive the nail properly, it is necessary that the driver bar, before its descent, be brought to a position directly over the perforations last made in the stock by the awl. In other words, the horizontal distance between the awl and the driver must be exactly equal to the length of the feeding stroke of the swinging head. If, therefore, the length of the feeding stroke of the awl be varied, as heretofore explained, it becomes necessary to adjust the relative positions of the awl and driver a corresponding amount. By the mechanism herein shown and described, a single adjustment obtained by manipulation of the handle member 70 will secure simultaneously adjustment of the awl in its position with respect to the driver and a corresponding adjustment in the feeding movement of the awl. The advantage of the construction thus described lies in the fact that the adjustment may be made with the greatest ease and the required degree of accuracy. A further advantage of the construction herein disclosed is found in the fact that the awl 12 may be secured in the awl carrier, by means of a plate 32, in such a way as to maintain the same always in true vertical alinement with the awl bar. Moreover, through the use of a plate like that shown at 32 accurate positioning of the awl with respect to the driver may be secured in setting up the machine and at other times should wear of the parts make such adjustment necessary.

The work rest 72 is provided with a slot 74 in which the fastening driving member and the awl move both in their reciprocations toward and from the work and also during their oscillatory movements as parts of the swinging head.

Having thus described my invention, what I claim as new and desire to secure by Letters Patent of the United States is:

1. In a fastening inserting machine, means for inserting fastenings comprising a driver, means for feeding the work to the inserting mechanism comprising an awl carrier and an awl carried thereby, and means mounted in the awl carrier for movement lengthwise thereof for adjusting the awl with respect to the driver.
2. In a fastening inserting machine, means for inserting fastenings comprising a driver, means for feeding the work to the inserting mechanism comprising an awl carrier and an

awl carried thereby, and means movable on the awl carrier for adjusting the awl with respect to the driver by relative movement of said means and the awl carrier.

5. In a fastening inserting machine, means for inserting fastenings comprising a driver, means for feeding the work to the inserting mechanism comprising an awl carrier and an awl carried thereby, and means bodily movable lengthwise of the awl carrier for causing adjustment of the awl toward or from the driver.

10. In a fastening inserting machine, means for inserting fastenings comprising a driver, means for feeding the work to the inserting mechanism comprising an awl carrier and an awl carried thereby, and means movable in directions toward and from the awl along a path closely adjacent to the vertical plane 20 of the awl and substantially parallel to the direction of penetrative movement of the awl for causing adjusting movement of the awl from or toward the driver.

15. In a fastening inserting machine, means for inserting fastenings comprising a driver, means for feeding the work to the inserting mechanism comprising an awl carrier and an awl carried thereby, and means movable in a right line lengthwise of the carrier for 30 causing adjusting movement of the awl toward or from the driver.

25. In a fastening inserting machine, means for inserting fastenings comprising a driver, means for feeding the work to the inserting mechanism comprising an awl carrier and an awl carried thereby, and means comprising a block slidably mounted in the awl carrier for movement along a path substantially 35 parallel to the direction of penetrative movement of the awl for causing adjusting movement of the awl toward or from the driver.

30. In a fastening inserting machine, means for inserting fastenings comprising a driver, means for feeding the work to the inserting mechanism comprising an awl carrier and an awl carried thereby, said inserting mechanism comprising a supporting frame, and means guided by the frame and by the awl carrier and movable relatively to both to 50 cause adjusting movement of the awl with respect to the driver.

35. In a fastening inserting machine, means for inserting fastenings comprising a driver, means for feeding the work to the inserting mechanism comprising an awl carrier and an awl carried thereby, said inserting mechanism comprising a supporting frame, and means comprising a member slidably mounted both in the frame and in the awl carrier 60 for causing the awl carrier to move toward or from the supporting frame, whereby the awl is adjusted toward or from the driver.

40. In a fastening inserting machine, means for inserting fastenings comprising a driver,

means for feeding the work to the inserting mechanism comprising an awl carrier and an awl carried thereby, and means movable in a right line for causing adjusting movement of the awl toward or from the driver and simultaneously corresponding adjustment in the extent of feeding movement of the feeding means.

45. In a fastening inserting machine, means for inserting fastenings comprising a driver, means for feeding the work to the inserting mechanism comprising an awl carrier and an awl carried thereby, and means bodily movable as a unit for causing adjusting movement of the awl toward or from the driver and simultaneously corresponding adjustment in the extent of feeding movement of the feeding means.

50. In a fastening inserting machine, means for inserting fastenings comprising a driver, means for feeding the work to the inserting mechanism comprising an awl carrier and an awl carried thereby, and means movable in directions from and toward the awl in a guideway in the awl carrier for causing adjusting movement of the awl toward or from the driver and simultaneously corresponding adjustment in the extent of feeding movement of the feeding means.

55. In a fastening inserting machine, means for inserting fastenings comprising a driver, means for feeding the work to the inserting mechanism comprising an awl carrier and an awl carried thereby, and means comprising a block slidably mounted in the awl carrier for causing adjusting movement of the awl toward or from the driver and simultaneously corresponding adjustment in the extent of feeding movement of the feeding means.

60. In a fastening inserting machine, means for inserting fastenings comprising a driver, means for feeding the work to the inserting mechanism comprising an awl carrier and an awl carried thereby, said inserting mechanism comprising a supporting frame, and means guided for movement in the frame and in the awl carrier for causing adjusting movement of the awl with respect to the driver and simultaneously corresponding adjustment in the extent of feeding movement of the awl.

65. In a fastening inserting machine, means for inserting fastenings comprising a driver, means for feeding the work to the inserting mechanism comprising an awl carrier and an awl carried thereby, said inserting mechanism comprising a supporting frame, and means comprising a member slidably mounted in the frame and in the awl carrier for causing adjusting movement of the awl with respect to the driver and simultaneously corresponding adjustment in the extent of feeding movement of the awl.

15. In a fastening inserting machine, means for inserting fastenings comprising a driver, means for feeding the work comprising an awl and an awl carrier having an inclined guideway therein, means for mounting the awl in the awl carrier for adjustment toward or from the driver, and means slidable along the inclined guideway in the carrier for causing adjusting movement of the awl with respect to the driver. 65
16. In a fastening inserting machine, means for inserting fastenings comprising a driver, means for feeding the work comprising an awl carrier and an awl, a frame for supporting the awl carrier, means for mounting the awl in the awl carrier for adjustment toward or from the driver, and means slidable as a unitary structure in said frame for causing adjusting movement of the awl with respect to the driver and simultaneously corresponding adjustment in the extent of feeding movement of the awl. 70
17. In a fastening inserting machine, means for inserting fastenings comprising a driver, means for feeding the work comprising an awl and an awl carrier having an inclined guideway therein, means for mounting the awl in the awl carrier for adjustment toward or from the driver, means comprising a block slidable along an inclined guideway in the carrier for causing adjusting movement of the awl with respect to the driver, and a work rest having an open-ended slot in which the awl may be adjusted and along which said awl moves in feeding the work. 75
18. In a fastening inserting machine, a reciprocatory head provided with an awl for perforating the work and for feeding the same, a driver, and means movable upon the awl carrier and toward and from the awl for adjusting the awl with respect to the driver and for causing corresponding adjustment in the extent of movement of the reciprocatory head. 80
19. In a fastening inserting machine, a swinging head provided with a driver and an awl, and means movable by translation as a single member for adjusting the awl with respect to the driver and for causing corresponding adjustment of the extent of swinging movement of the head. 85
20. In a fastening inserting machine, a driver, a frame for supporting the driver and having a guideway therein, means for perforating the work, means for feeding the work to the driver constructed and arranged to place the perforations successively beneath the driver that fastenings may be driven therein, and means bodily movable in said guideway for varying the spacing between perforations and for adjusting the feeding means to correspond to the changed spacing. 90
21. In a fastening inserting machine, a head having a driver-bar and an awl-bar carrying, respectively, a driver and an awl, means for moving the driver-bar and the awl-bar alternately into and out of the line of drive of the fastenings, and means slidable as a unitary structure for adjusting the awl with respect to the driver and for effecting a corresponding adjustment in the moving means for driving-bar and awl-bar. 95
22. In a fastening inserting machine, a head having a driver-bar and an awl-bar carrying, respectively, a driver and an awl, means for moving the driver-bar and the awl-bar alternately into and out of the line of drive of the fastenings, and means movable as a single member toward and from the awl along a path parallel to the direction of penetrative movement of the awl for adjusting the awl with respect to the driver and for effecting a corresponding adjustment in the moving means for the driver-bar and awl-bar. 100
23. In a fastening inserting machine, a driver, a supporting frame for the driver provided with a guide-way, an awl, a carrier for said awl mounted for oscillation, and means movable along said guideway in the supporting frame for adjusting the awl with respect to the driver and for controlling the oscillation of the awl carrier. 105
24. In a fastening inserting machine, a driver, a supporting frame for the driver mounted for reciprocation and provided with an elongated guideway, an awl, a carrier for the awl mounted for oscillation and provided with an elongated guideway, and means movable along both guideways for controlling the oscillation of the awl and its spacing with respect to the driver. 110
25. In a fastening inserting machine, a driver, a supporting frame for the driver mounted for reciprocation and provided with an elongated guideway, an awl, a carrier for the awl mounted for oscillation and provided with an elongated guideway, the directions of the major axes of the guideways being inclined to each other, and means movable as a unitary structure along both guideways for controlling the oscillation of the awl and the spacing thereof with respect to the driver. 115
26. In a fastening inserting machine, means for inserting fastenings comprising a driver and a supporting frame carrying the driver and mounted for to and fro movement on the machine, means for feeding the work to the fastening inserting mechanism upon movement of the supporting frame in one direction, comprising an awl, said supporting frame being formed at its lower end with a portion disposed on the side of the driver opposite to the direction of movement of the frame while the work is being fed, 120
- 125

operating means for the frame comprising an element co-acting with such portion of the frame, and means operatively connected with the operating means for adjusting the 5 awl with respect to the driver.

27. In a fastening inserting machine, means for inserting fastenings comprising a driver and a supporting frame carrying the driver and mounted for to and fro movement on the machine, means for feeding the work upon movement of the supporting frame in one direction comprising an awl, said supporting frame being formed at its lower end to present a portion disposed on 10 the side of the driver opposite to the direction of movement of the frame during the feeding of the work, operating means for the frame constructed to enable the extent of the to and fro movements of the frame and, consequently, the extent of feeding movement of the work to be varied and comprising an element coacting with said portion of the frame, and means operatively connected with the operating means for simultaneously moving the awl toward or 15 from the driver in a corresponding degree when the extent of feeding movement of the work is varied.

28. In a fastening inserting machine, means for inserting fastenings comprising a driver and a supporting frame carrying the driver and mounted for to and fro movement on the machine, means for feeding the work to the inserting mechanism upon movement of the frame in one direction comprising an awl, means for imparting to and fro movement to the supporting frame comprising a channeled arm disposed rearwardly of the frame and a device slidably 20 adjustable as a unit in the channel of the arm and in the frame to vary the extent of to and fro movement imparted to the frame, and means operatively connected with the

device for adjusting the awl with respect to the driver.

29. In a fastening inserting machine, means for inserting fastenings comprising a driver and a supporting frame carrying the driver and mounted for to and fro movement on the machine, means for feeding the work to the inserting mechanism upon movement of the frame in one direction comprising an awl carrier and an awl carried thereby, said supporting frame being constructed at its lower end with a portion disposed on 5 the side of the driver opposite from the direction of movement of the frame during the feeding of the work and provided with a slot, means for imparting to and fro movement to the supporting frame comprising an arm, connections between the supporting frame and the arm including a member movable in the slot of the supporting frame to vary the extent of to and fro movement imparted thereto and, consequently the extent of feeding movement of the work, and means movable with said member for simultaneously adjusting the awl correspondingly toward and from the driver when the extent of feeding movement of the work is varied.

30. In a fastening inserting machine, means for inserting fastenings comprising a driver, means for feeding the work to the inserting mechanism comprising an awl, an awl bar, and an awl bar carrier, means 75 mounted on the machine frame independently of the awl bar carrier to cause the awl to penetrate the work and to withdraw the awl from the work, and means for simultaneously causing adjusting movement of 80 the awl toward or from the driver and corresponding adjustment of the extent of feeding movement of the work.

In testimony whereof I have signed my name to this specification.

GEORGE GODDU.
